[57] **CLAIM**

The ornamental design for the ribbed housing for lock, as shown and described.

DESCRIPTION

FIG. 1 is a top perspective view of the ribbed housing for lock of the present invention;

FIG. 2 is a bottom perspective view of the ribbed housing for lock of FIG. 1;

FIG. 3 is a front elevation view of the ribbed housing for lock of FIG. 1; the back elevation view is a mirror image;

FIG. 4 is an elevation view of the right side of the ribbed housing for lock of FIG. 1;

FIG. 5 is an elevation view of the left side of the ribbed housing for lock of FIG. 1;

FIG. 6 is a top plan view of the ribbed housing for lock of FIG. 1; and,

FIG. 7 is a bottom plan view of the ribbed housing for lock of FIG. 1.

The phantom line disclosures of the shackles are shown for illustrative purposes only and form no part of the claimed design.
